ATTORNEY.

UNITED STATES PATENT OFFICE

123,578

DESIGN FOR AN ELECTRIC SOLDERING IRON

Milton H. Shoenberg, San Francisco, Calif.

Application August 24, 1940, Serial No. 94,609

Term of patent 14 years

To all whom it may concern:

Be it known that I, Milton H. Shoenberg, a citizen of the United States and a resident of the city and county of San Francisco, State of California, have invented a new, original, and ornamental Design for an Electric Soldering Iron, of which the following is a specification, reference being had to the accompanying drawing, forming a part thereof.

Fig. 1 is a side elevation of my electric soldering iron showing my new design.

Fig. 2 is a plan view of the electric soldering iron shown in Fig. 1.

I claim:

The ornamental design for an electric soldering iron, substantially as shown.

MILTON H. SHOENBERG.
